UNITED STATES PATENT OFFICE.

HENRY A. WEIHMAN, OF PHILADELPHIA, PENNSYLVANIA, ASSIGNOR TO JOHN F. SIMONS AND THOMAS MADDOCK, OF SAME PLACE, FREDERICK M. SIMONS, OF SWARTHMORE, PENNSYLVANIA, AND EDWIN S. SIMONS, OF ORANGE, NEW JERSEY, (TRADING AS SIMONS, BROTHER & COMPANY.)

DESIGN FOR A BACK FOR BRUSHES OR SIMILAR ARTICLES.

SPECIFICATION forming part of Design No. 34,813, dated July 23, 1901.

Application filed June 12, 1901. Serial No. 64,334. Term of patent 3½ years.

To all whom it may concern:

Be it known that I, HENRY A. WEIHMAN, of the city and county of Philadelphia, State of Pennsylvania, have invented and produced a new and original Design for Backs for Brushes or Similar Articles, of which the following is a specification.

My invention is a new and original design for backs of brushes and similar articles, of which the following is a specification, reference being had to the accompanying drawing.

In the drawing is illustrated a plan view of the back of a brush, showing my design.

The general outline of the back is pandurate, and the characteristic features of the ornamentation comprise the representation of a water-lily leaf with upturned edges, forming the outer boundary *h* of the back; a water-lily effect *g c e f*, arranged around the han-

dle and back, and the figure *d* of a nymph 20 arranged adjacent to one edge of the back.

The central surfaces *a* and *b* of the back and handle, respectively, are unornamented.

The floral design *g c e f* and the figure *d* are highly embossed in order to make them 25 stand out in high relief.

Having described my invention, what I claim as new, and desire to secure by Letters Patent, is—

The design for a back for brushes and similar articles, as herein shown and described.

In testimony of which invention I have hereunto set my hand.

HENRY A. WEIHMAN.
